UNITED STATES PATENT OFFICE.

WILLIAM M. CUMMER, OF CLEVELAND, OHIO.

MECHANICAL DRIER

No. 888,474.

Specification of Letters Patent. Patented May 26, 1908.

Application filed September 3, 1907. Serial No. 391,151.

To all whom it may concern:

Be it known that I, WILLIAM M. CUMMER, a citizen of the United States, residing at Cleveland, in the county of Cuyahoga and State of Ohio, have invented certain new and useful Improvements in Mechanical Driers, and do declare that the following is a full, clear, and exact description of the invention, which will enable others skilled in the art to 10 which it appertains to make and use the same.

My invention relates to mechanical driers, and the invention consists in the construction and combination of parts substantially 15 as shown and described and particularly pointed out in the claims.

In the accompanying drawings, Figure 1 is a longitudinal sectional elevation of the drier cylinder and of my new and original installation or setting thereof with furnace and inclosing walls. Fig. 2 is a side elevation of a 20 longitudinal portion of section of the cylinder and Fig. 3 is a cross section of Fig. 2. Fig. 4 is a cross section of a complete cylinder in its 25 central portion and of the setting therefor in working relation.

Having reference first to the setting or walls of cylinder C, I show an inclosed chamber about a portion thereof constructed with 30 a short arch A beneath and side walls a, inclosing section —3— of the cylinder. This leaves the first section or portion —2— of the cylinder more or less directly exposed to the products of combustion from furnace F, but there is no outlet from about this section or 35 space except at the bottom, so that the products of combustion must pass thence rearward. The said walls a closely encircle cylinder C and are each provided with openings 40 —5— controlled by suitable dampers —6— from the outside, and openings —7— closed by doors —8— in the outer sides or wall of the setting to admit more or less fresh air as occasion may demand. Hence, also the 45 temperatures within said walls and chamber are under the absolute control of the operator.

In drying some materials it is desirable that the temperature should be lower at the front or supply end of the cylinder than with 50 others, and that it should be gradually increased toward the rear or discharge end. Yet it may be necessary that the shell of the cylinder should have at least sufficient heat at all points to prevent certain substances 55 from sticking or adhering to the surface thereof. Some substances also will not permit

heating to a very high degree before a certain amount of moisture has been taken off, for the reason that, if heated and having a certain temperature before moisture be taken off, they become soluble in their own moisture and adhere to the internal parts of the cylinder. The style of setting herein and the construction of the cylinder itself, are adapted to take care of these varying conditions, 65 characteristics and needs of all materials.

Now, referring especially to the construction of the cylinder, the same is built in its main or middle portion, sections 3 and 4, with a series of lengthwise sheets S, segmental in cross section in their main portion and curved according to the diameter of the cylinder. Said sheet or plates S are also provided with inwardly extending portions having compound curvatures —12— and inner 70 guard and lift portions —14— and —15— integral or affixed. The said curvatures —12— start with a rather short inward bend at nearly right angles to the convex surface of plate S and then recurve to their engagement 75 with channel-bars D. This affords ample room between the said segments for the inflow of air through said channel-bars as well as serving partially as guards for inlet air passages or openings —17—.

The respective sections S, are riveted lengthwise to the flanges of said channel-bars D, and the draft inlets or openings —17— in said bars are in such number and size that they permit the products of combustion and 80 heated air to enter the cylinder in the desired volume. Of course, some of said products and heated air will pass to the rear and enter through the open end of the cylinder, and the said channel-bars in this instance are co-extensive with plate S, while end sections —2— and —9— are closed about their sides. The 85 said portions —14— and —15— of plates S serve both as lift blades for the material and as guards for the draft openings, and special 90 guard blades L are located lengthwise inward from bars D on suitable brackets —19— affixed to the wall of the cylinder C and are of such elevation or width as compared with 95 said guards —14— and —15— as to permit 100 inward curving at —20— over and above edge —15— and to overlap the same in a sheltering manner while at the same time ample draft space is preserved between said 105 blades or guards. The bend —20— being 110 in the shape of a curve and not a sharp corner prevents accumulation of material thereon.

Guards L are set apart from the wall of the cylinder on brackets —19— to let material pass inward beneath the same as it works back from about the draft openings. The speed of rotation is such as to allow of the pockets between plates L and guards —14— being completely emptied during their travel through the period of cascading, and six to ten revolutions per minute serve this purpose. Now, as a new and important improvement in this class of cylinders, I provide the inlet or draft openings through channel-bars D with special guards G on their outside. These guards are open at both ends and have openings at their bottom or sides which register with openings —17— in bars D, and the ends of said guards have inwardly extending flanges φ which serve to intercept dust and material that otherwise might creep out and which is detained thereby and returned to the cylinder when the cylinder turns around. By these means I prevent all escape of material in any form through the said draft openings or channels —17—, while at the same time the said channels are unobstructed for the purposes of draft inlet. Furthermore, and to more clearly appreciate the value of guards G in this machine, I may state that the suction fan usually placed in chamber M is driven independently of the cylinder, and there is a likelihood, at times, of the fan being stopped or slackened down in its speed while at the same time the cylinder is going at the usual rate of speed. In that case any dust or small specks coming from the material in the drier is intercepted and returned, and this so far as I know and believe has never been done before.

When blades —14— and L are in the lower position during rotation they serve especially as guards to prevent cascading material from falling into the pockets between them and thus also preventing the draft openings from being closed. When said blades are past the center of rotation on the cascading side they become lift-blades, adapted to cascade the material as they rise to higher elevations. Blades N cascade the material in like manner. These latter blades are curved inward at their inner edges instead of being at approximately right angles as heretofore, whereby they effectually prevent the accumulation of material thereon. By these means, also, the material is cascaded more effectively across the entire area of the cylinder than heretofore without incurring the danger of carrying some of it around before cascading occurs, and in which event it would fall on the back of the preceding angle and thus deprive this portion of the material of a proper amount of exposure through the circulating air and heat. Said blades N extend the entire length of the cylinder.

In driers of this class there are various reasons why the cylinder should have one or both ends plain and draft openings with guards only in or along the middle portion thereof, and particularly in connection with certain materials as herein set forth. The plain cylindrical ends —2— and —9— are concentric with the curvature of segments S, and hence there is no obstruction from one section to the other and the flow of the material is uniform and continuous through the cylinder. Attention is also expressly called to the formation of plates S at the outside of channel bars D, where the primary curve of said plates carries them inward away from said bars and from over guards G in such measure as to afford free open draft-ways through the ends of said guards into the cylinder. Of course any equivalent construction of outer guards G may be adopted. 85

What I claim is:—

1. In a mechanical drier, a setting for a drier cylinder having a walled chamber in the line of draft provided with damper controlled draft openings. 90

2. A setting for a drying cylinder provided with a chamber adapted to inclose a section of the cylinder, said chamber having an arched bottom and draft openings into the same. 95

3. A setting for a drying cylinder having a suitable furnace, a walled chamber apart from the furnace adapted to inclose a portion of the cylinder and an open space between said chamber and furnace adapted to expose the front portion of the cylinder therein directly to the products of combustion. 100

4. A setting for a drying cylinder constructed with a walled chamber having an arched bottom and draft controlled openings entering the same, and a cylinder having an imperforate portion exposed in front of said chamber and a perforated portion in said chamber. 105

5. A setting for mechanical driers having a chamber provided with draft openings and dampers for said openings, in combination with a drying cylinder having draft openings exposed in said chamber, whereby controlled draft is afforded to a portion of said cylinder. 110

6. A mechanical drier comprising a cylinder having plain cylindrical ends and a middle portion provided with draft inlets, in combination with a setting for the cylinder having a walled chamber inclosing a portion of said cylinder and provided with openings to direct the products of combustion through the same into the cylinder. 115

7. A drying cylinder having imperforate cylindrical ends and a portion between said ends having draft openings through the wall thereof and guards on the outside of said openings. 120

8. A drying cylinder having plain end 125

portions and a middle portion constructed with plates segmental in cross section in their main portion, and spacing members provided with draft openings at intervals 5 rigidly uniting said plates.

9. A drying cylinder having plain cylindrical ends and a portion between said ends formed of a series of segmental plates lengthwise thereof, and channel members connecting said plates provided with draft openings, said plates each having inwardly curved portions engaged with the inner flanges of said channel members.

10. A drying cylinder having a portion 15 thereof formed of plates segmental in cross section in their main portion and with compound curves in their other portion, and angle-bars having draft openings connecting said plates between opposite edges respectively, whereby the compound curved portion of each plate will come outside of the corresponding angle-bar and a free draft space into the cylinder is afforded.

11. A drying cylinder formed with plates 25 running longitudinally and curved in cross section in their outer portion and each having an inwardly curved inner portion, and rigid angle-bars uniting the outer edge of one plate and the inner curved portion of another 30 plate on different edges thereof, said bars provided with draft openings, and guards over the outside of said openings.

12. In drying cylinders, a cylinder constructed with plates running lengthwise between its ends and curved transversely to the curvature of the cylinder in their main portion, channel bars uniting said plates and each plate having an inwardly curved portion fixed to the inner flange of the corresponding bar, said bars having draft openings, and guards about said openings.

13. A drying cylinder having successive draft openings through the same and substantially barrel shaped guards over said openings having open internally flanged ends 45 and openings in their bottoms registering with said draft openings.

14. The drying cylinder formed with plates running lengthwise segmental in cross section in their main portion and secured to opposite edges of channel-bars successively, said channel-bars set at right angles to the periphery of the cylinder and provided with a series of draft openings through the web thereof, and guards about 50 both the inside and the outside of said draft openings.

15. A drying cylinder having openings through the shell thereof for admission of products of combustion and guards with 60 open ends over the outside of said openings.

16. A drying cylinder having inlet openings at intervals, in combination with guards over the outside of said openings open at 55 both ends.

17. A drying cylinder having inlet openings, in combination with substantially barrel shaped guards therefor having open ends and openings in the side corresponding to 65 said openings in the cylinder.

18. A drying cylinder having straight and flat sided parts running lengthwise and provided with inlet openings, in combination with guards fixed over said openings on the outside of said cylinder.

In testimony whereof I sign this specification in the presence of two witnesses.

WILLIAM M. CUMMER.
